UNITED STATES PATENT OFFICE.

CHARLES BRITTAINE DRAKE, OF NORFOLK, VIRGINIA.

VALVE.

Application filed October 11, 1926. Serial No. 140,929.

My invention relates to new and useful improvements in valves and more particularly to a thermostatically controlled valve adapted for use with carburetors for internal combustion engines for regulating the supply of fuel to the intake manifold.

The principal object of the invention resides in the provision of a novel construction wherein the thermostatic member is connected directly to the valve stem and in which the valve stem is adapted to have sufficient movement relative to the thermostatic member and the bushing through which it extends so that the end of the stem may properly engage in the valve seat.

A further object of the invention consists in the provision of novel means for conducting heat to the thermostatic member whereby the valve is adjusted.

With the above and other objects in view I will now proceed to describe the preferred embodiments of the invention but it will be understood that such changes may be made as will fall within the scope of the appended claims.

In the drawings:

Fig. 1 is an elevation, with parts broken away, showing the manner of connecting my improved form of valve to the engine carburetor and associated parts.

Fig. 2 is a longitudinal vertical section through the valve with parts shown in elevation.

Fig. 3 is a horizontal section on the line $x-x$ of Fig. 2 looking in the direction of the arrows, and

Fig. 4 is a transverse vertical section on the line $y-y$ of Fig. 3.

It is a well known fact that in the use of internal combustion engines that it is desirable in initially starting to use a relatively rich mixture and then when the engine has been running a short time to feed a leaner mixture. With my improved form of valve the mixture is automatically regulated by the heat of the engine, the richness of the mixture being reduced after the engine has become heated.

In the drawings the numeral 1 indicates a vaporizing device used in connection with certain forms of carburetors and engines and 2 indicates the carburetor of usual or well-known construction having the valve seat 3. My improved form of valve includes an exteriorly threaded bushing 4 which is adapted to be received in a threaded opening formed

in the top of the carburetor. The bushing 4 is provided at the top with the interiorly threaded opening 5 into which is threaded the sleeve or bushing 6, said sleeve or bushing 60 having the flange 7 formed intermediate its ends. A lock nut 8 is received upon the sleeve or bushing 6 and is adapted to engage the upper end of the bushing 4 as shown more particularly in Fig. 2 of the 65 drawings.

A plate 9 is adapted to be received upon the flange 7, said plate having an opening 10 through which the upper end of the sleeve or bushing 6 extends, the opening 70 being of such a diameter as to allow longitudinal movement of the plate relative to the sleeve or bushing. One end of the plate 9 is bent to form the eyes 11 and the opposite end is bent upwardly to form the extension 12 more particularly illustrated in Fig. 2. A leaf spring 13 engages the upper face of the plate 9, being provided with a central opening through which the upper end of the sleeve or bushing 6 extends, and a 80 nut 14 is received on the upper threaded end of the sleeve or bushing 6 and engages the upper surface of the spring. The spring normally holds the plate 9 in tight engagement with the flange 7 and holds the nut 85 14 in its adjusted positions.

The thermostatic member is shown at 15 and has one end bent to form the extension 16 engaging the underside of the plate 9. A screw 17 or other suitable fastener extends 90 through the extension 16 for securing the same to the plate 9. The opposite end of the member 15 is forked as shown at 18 and engages in the groove 19 formed adjacent the upper end of the valve stem 20. 95 The groove 19 is provided with the upper and lower beveled surfaces 21 and 22 for a purpose which will be later described. The lower end of the valve stem is pointed as shown at 23 to engage in the valve seat 3 100 of the carburetor. A groove 24 is formed intermediate the ends of the valve stem 20 and a ring 25 is received in said groove and adapted to engage the lower end of the sleeve or bushing 6 to limit the upward 105 movement of the valve stem. The longitudinally extending bore of the sleeve or bushing 6 is of slightly greater diameter than that of the valve stem to cooperate with the beveled surfaces 21 and 22 of the groove 110 19 to allow the lower or pointed end of the stem to swing slightly in any direction

whereby it will properly engage the seat 3.

For enclosing the thermostatic member I provide the cover 26 which is hingedly connected to the plate 9 by passing the lower 5 end of the conductor rod 27 through the eye 11 of the plate 9 and the sides of the cover. The upper end of the conductor rod 27 is secured to the vaporizer 1 by means of the bolt 28 or other suitable means. The 10 free end of the cover 26 will engage the upwardly extending portion 12 of the plate 9 and be held in its closed position by frictional engagement. An upwardly extending projection 29 is struck from the plate 15 9 and extends into the notch 30 formed in one end of the spring 13. This allows for movement of the spring longitudinally when the nut 14 is adjusted but prevents sidewise movement of the spring relative to the plate.

20 From the above detailed description it is thought that the construction of my improved form of valve will be clearly understood. Particular attention is directed to the fact that the thermostatic member is 25 connected directly to the valve stem and by having the valve stem of less diameter than the bushings through which it passes and by providing the beveled surfaces 21 and 22 for the groove 19 in which the forked end 30 of the thermostatic member engages the lower or pointed end of the valve stem may swing slightly in any direction so that it will properly engage the seat 3. In certain forms of carburetors with which my valve 35 will be used there is not precision construction and there might not be an exact aligning of the valve stem and valve seat. By allowing for the described movement of the lower end of the valve stem the same may 40 properly engage the valve seat. When the engine is cold the pointed end of the valve stem will be positioned away from the valve seat 3 to allow for a relatively rich mixture of fuel. As the engine becomes heated heat 45 is conducted through the conductor rod 27 to the thermostatic member 15 and as the same becomes heated the valve stem is lowered so that the pointed end of the valve stem will be nearer the seat 3 and reduce the 50 richness of the mixture. Heat will also be conducted through the valve stem to aid in preheating the raw fuel to make it more volatile. The nut 14 will limit the downward movement of the valve stem by the 55 end of the thermostatic member engaging the upper surface of the nut.

Having fully described my invention what I claim as new and desire to secure by Letters Patent is:

60 1. A valve of the character described including a sleeve having a flange formed thereon, a plate adapted to be received upon

said flange, a valve stem slidable relative to the sleeve, and a thermostatic member connected to the plate and to the valve stem. 65

2. A valve of the character described including a sleeve having a flange formed thereon, a plate adapted to be received upon said flange, means for holding the plate in engagement with the flange, a valve stem 70 slidable relative to the sleeve, and a thermostatic member connected to the plate and to the valve stem.

3. A valve of the character described including a sleeve having a flange formed 75 thereon, a plate adapted to be received upon the flange, means for holding the plate in engagement with the flange, a valve stem slidable through the sleeve and having a circumferentially extending groove, and a 80 thermostatic member having one end secured to the plate, the opposite end of the member being forked for engagement in the groove.

4. A valve of the character described including a sleeve having a flange formed thereon, a plate adapted to be received upon the flange, a valve stem slidable relative to the sleeve, a thermostatic member connected to the plate and to the valve stem, and means 90 carried by the sleeve and adapted to be engaged by the thermostatic member for limiting the downward movement of the stem. 95

5. A valve of the character described including a sleeve having a flange formed thereon, a plate adapted to be received upon the flange, a valve stem slidable relative to the sleeve, a thermostatic member connected to the plate and to the valve stem, and adjustable means carried by the sleeve and 100 adapted to be engaged by the thermostatic member for limiting the downward movement of the stem. 105

6. A valve of the character described including a sleeve having a flange formed thereon, a plate adapted to be received upon the flange, a valve stem slidable relative to the sleeve, a thermostatic member connected to the plate and to the valve stem, and an adjustable nut carried by the sleeve and adapted to be engaged by the thermostatic member for limiting the downward movement of the stem. 110

7. A valve of the character described including a body portion, a valve stem slidable through the body, a thermostatic member connected to the body and to the valve stem, and adjustable means carried by the body and adapted to be engaged by the thermostat for limiting the downward movement of the stem. 115

In testimony whereof I hereunto affix my signature.

CHARLES BRITTAINE DRAKE.
